CLAIM

The ornamental design for an integrated air compressor and winch, as shown and described.

DESCRIPTION

FIG. 1 is a front perspective view of an integrated air compressor and winch;

FIG. 2 is a front planar view thereof;

FIG. 3 is a top view thereof;

FIG. 4 is a right side view thereof; and,

FIG. 5 is a left side view thereof.

It being understood that the broken lines are for illustrative purposes only and form no part of the claimed design.

In the drawings, the evenly spaced broken lines represent unclaimed environmental structure of the described environmental structure; dash-dot-dot-dash broken lines represent the boundaries of the claim and form no part of the claimed design.
